UNITED STATES PATENT OFFICE.

JOHN A. VOSKAMP, OF NEW YORK, N. Y., ASSIGNOR TO IRVING IRON WORKS COMPANY,
A CORPORATION OF NEW YORK.

ARMORED REINFORCED-CONCRETE SLAB.

Application filed October 25, 1926. Serial No. 143,809.

This invention is an improvement on the structure described in U. S. Patent to Walter E. Irving, No. 1,524,035 dated January 27, 1925, and is designed to reduce the weight of such structure without correspondingly decreasing its strength. It is particularly designed for use on bridges in which the floor plates or slabs rest on sills extending crosswise of the bridge. The best form of apparatus at present known to me embodying my invention and certain modifications thereof, are illustrated in the accompanying sheet of drawings in which

Fig. 1 is a diagrammatic plan view of a part of a bridge structure with cross sills, showing a part of the reenforced flooring, parts being broken away.

Fig. 2 is a perspective skeleton view on a larger scale showing certain extended skeleton bars serving as vertical spacing elements.

Fig. 3 shows a modification of the structure shown in Fig. 2 in which lower horizontal spacing strips have been omitted and all straight bars extended in skeleton form.

Fig. 4 shows a further skeletonized modification.

Throughout the drawings like reference characters indicate like parts. 41, 41, represent the trusses of a bridge the deck or floor 43 of which is supported by cross sills 42, 42. Said deck or floor is formed by reenforced concrete slabs or sheets stretching across from one sill to another. The invention relates to the reinforcement of these concrete slabs, and comprises a grating embedded in the concrete at or near the upper surface thereof and serving as a skeleton armoring for said surface and as means for distributing the shearing stresses created by a concentrated load, and a set of tension reenforcing members parallel to the longitudinals of said grating, supported therefrom, and embedded in the lower portion of the slab. These lower tension reenforcing members may be connected together to form a second grating. In any case they are supported from the upper grating by skeleton means to save weight.

The grating embedded in the upper surface of the slab is preferably formed of parallel straight bars 31, 31, spaced apart by intervening bent strips 33, these elements being riveted together as shown at 35, 35. One form of tension reenforcement for the lower portion of the slab consists of the straight

bars 32 and 32^a, shown in Fig. 2, these being connected together by intervening bent strips 34, 34, to form a second grating which is supported from the upper grating by extending certain of the bars marked 32^a vertically 60 in skeletonized form so that their upper portions may serve as certain of the straight bars for the upper grating. Preferably the skeleton structure is formed by stamping or cutting out portions 40, 40, from the medial 65 section of each wide bar. 37 is a body of concrete filling the meshes of both gratings and the space between gratings, including the cut-out spaces 40, 40.

Where great rigidity is required all of the 70 straight bars 31 may be extended in skeleton form to serve as tension members 32^a, as shown in Fig. 3. In such case, the lower bent spacing strips may be omitted, as there shown, the horizontal spacing action of the 75 upper strips 33 being sufficient. Any desired number of transverse reenforcing and binding members such as rods 38, 38, may be inserted through certain of the cut-out spaces 40 to tie the parts together and further distribute the load laterally.

When lighter loads are to be carried the tension reenforcement may consist merely of rods 32^b, as shown in Fig. 4, supported from the upper grating by hooks 39 through 85 the eyes 39^b of which the rods 32^b extend, while the hooked ends 39^a pass through holes 36 in the straight bars 31 of the grating which forms the surface armor.

In laying or building up the slabs to form 90 the bridge deck 43 it is important that the longitudinals of the surface grating extend lengthwise of the bridge, i. e. parallel to the flow of traffic, so that the wide tires of the wheels of heavy motor trucks may rest on as 95 many of the grating bars as possible and so distribute the concentrated load on said wheels as widely as possible, thereby reducing the punching shear stresses developed per unit of area in the slab beneath each 100 wheel. The form of slab here shown is designed to accomplish this result on bridges in which the floor sills run at right angles to the flow of traffic, as indicated by the arrow in Fig. 1, and still have the lower, tension 105 reenforcing means extending across said sills.

The skeletonizing of the longitudinals which serve as spacing members between the upper and lower reenforcing means, as 110

- shown in Fig. 2, produces a truss-like structure of great strength per unit of weight. These results are usually attained in the highest degree in the form shown in Fig. 3.
- 5 The rigidity so secured enables the bridge designer to specify deck slabs of much reduced thickness and consequent less weight of concrete, and also to cut down the weight of reenforcing metal used in the structure
- 10 shown in the above mentioned Irving patent to support a given load. This permits a corresponding reduction in the metal needed for the bridge girders, trusses or cables, towers, etc. which, in turn, produces a further
- 15 saving in dead load carried by the structure with the net result that the cost of the bridge parts, other than the decking or flooring, is reduced by an amount more than enough to pay for the cost of the latter.
- 20

Having described my invention, I claim:

1. A structure adapted to serve as a reinforcement in concrete slabs, which structure comprises the combination of two similar gratings, each composed of a series of 25 straight bars and a series of bent strips, each of which strips is located between, and fastened to, the straight bars of either side of it, a few of said straight bars uniformly spaced apart being wide enough to extend 30 from one grating to the other and form an element in each, and having the portions between said gratings cut away into skeleton form.
2. The combination of a structure such as 35 defined in claim 1 with a body of concrete filling the meshes of said gratings, the space between said gratings and the cut away portions of said skeleton bars.

JOHN A. VOSKAMP.
